UNITED STATES PATENT OFFICE.

GEORGE SCHRADE, OF NEW YORK, N. Y., ASSIGNOR TO M. E. THAYER AND DELA THAYER, OF SAME PLACE.

PIN FOR NECK-WEAR.

SPECIFICATION forming part of Letters Patent No. 376,047, dated January 3, 1888.

Application filed June 19, 1886. Serial No. 205,644. (No model.)

To all whom it may concern:

Be it known that I, GEORGE SCHRADE, of the city of New York, in the county and State of New York, and a citizen of the United States 5 of America, have invented certain new and useful Improvements in Detaining Pins, of which the following is a specification, reference being had to the accompanying drawings, forming part of the same, in which—

10 Figure 1 is a side elevation of my new pin, showing the upper end bent at right angles to the body, but in the plane of the principal parts of the pin. Fig. 2 is a view of such pin, but with its upper end bent at right angles to the plane of said principal parts. Fig. 3 represents the pin of Fig. 1 so combined with a shield that the point and the main body of the pin are upon opposite sides of the shield. Fig. 15 4 represents said pin and shield so combined that the point and main body are on the same side of the shield. Fig. 5 is a view of the pin shown in Fig. 2 secured to the shield at the lower end, as is that of Fig. 4, but at the upper end by being passed through the shield and 20 pressed down tightly upon it; and Fig. 6 is a modification of said pin, in which the loops are given the form of a **Z** rather than that of an **S**, which I consider substantially equivalent, but not quite so desirable.

25 My invention relates to a pin adapted to be secured to a necktie-shield, and when so placed to act to hold the free end of the neckband of the necktie or scarf, to which the shield is affixed in the ordinary manner; and it consists 30 in the form of the pin, and in its combination with the shield in the manner specified. The pin may be formed by taking a piece of stout wire, preferably pointed at both ends, though a point at only one end may be used, and bending it back upon itself, thus forming a loop, *a*, then bending it again back upon itself away from the point, forming a second loop, *b*; and a special advantage is gained by making this second loop at such a distance from the first, 35 and that at such a distance from the point, that (both being preferably short) loop *b* shall extend to opposite a point upon the lower or point end of the shield from which it is intended the end of said pin shall project beyond the shield. 40 After making loop *b*, I usually bend the upper end of the pin at an angle to the body thereof, as shown in Fig. 2; but it is almost equally serv-

iceable when bent as shown in Fig. 1, or at some other than a right angle, which will enable me to secure it to the shield by passing it 45 through the same at that point. Indeed it would be entirely sufficient to bend it into a circle or curve, through which and the shield an eyelet might be passed, which being spread open would make an excellent fastening. I have shown the loops *a* and *b* as together forming an **S**; but if they were so sharply bent as to form a **Z**, or such, for instance, as seen in Fig. 6, it would be sufficient, my main desire being and my invention having for its basis 55 the forming of a pin with a loop the opening of which shall be in a direction away from the point, to do which the first loop of course becomes a necessity, or the first loop, to do which the second is a necessity. The body of the pin 60 between the loop and the upper bend, *c*, I preferably make nearly equal in length to the depth of the shield, as by that means it acts as a stiffener thereof, which in the case of cloth shields for use in Teck scarfs is a great advantage.

In securing the pin to the shield I may insert the point into the same until held from further downward movement by loop *a*, and then pass the upper end through the upper 65 part of the shield, thereby securing the pin, adding a thread fastening, if desired, as at *d*; or I may so enter the point, and then pass the main body of the pin down and about the lower edge of the shield, bringing it up again 70 on the opposite side, (the same side with the point,) and then secure the upper end—as, for instance, by passing it through the shield and pressing it down, as seen in Fig. 5; but either other mode makes a good fastening. When 75 thus made and applied, this pin is the most secure of any known. It cannot slip down, for loop *a* and the end beyond angle *c* bear against the shield to prevent movement in that direction. It cannot slip up, for loop *b* bears 80 against the lower edge of the shield to prevent movement in that direction. It is therefore specially adapted for use in Teck scarfs, as it can be as easily secured to a flexible cloth shield as to one of stiff card-board, and it is 85 held thereon with equal certainty.

What I claim as my invention, and desire to secure by Letters Patent, is—

1. The combination of a shield and a retain-

ing-pin having a point, a loop next said point which opens toward it, a second loop beyond the first and opening away from the point, and a body extending from said second loop, said point-loops and body being in substantially the same plane, all as and for the purpose specified.

2. The combination of a shield and a retaining-pin having a point, a loop next said point and opening toward it, a second loop beyond the first and opening away from the point, and a securing device, substantially as specified.

3. The combination of a shield and a retaining-pin having a point, a loop next said point and opening toward it, and a second loop beyond the first and opening away from it, all substantially in the same plane, and the attaching body portion, substantially as and for the purpose specified. 15

GEORGE SCHRADE.
